UNITED STATES PATENT OFFICE.

DONALD R. CORBIN, OF NEW YORK, N. Y.

DESIGN FOR A SCARF-PIN OR SIMILAR ARTICLE.

SPECIFICATION forming part of Design No. 29,055, dated July 19, 1898.

Application filed May 25, 1898, Serial No. 681,743. Term of patent 3½ years.

To all whom it may concern:

Be it known that I, DONALD R. CORBIN, a citizen of the United States, residing in New York city, county of New York, State of New York, have invented and produced a new and original Design for a Scarf-Pin or Similar Article, of which the following is a specification, reference being had to the accompanying drawings, forming part thereof.

10 Figure 1 is a plan view of my scarf-pin or similar article. Fig. 2 is an edge view thereof, and Fig. 3 is a rear elevation of the same.

As shown in the drawings, the leading or material features of my design consist of a 15 series of signal-flags A, connected to a line or rope b, said line or rope being attached at its opposite ends to a staff a, having a ball or similar device d at its upper end. Between the line and pole a b the badge is solid, 20 or not cut away to form an outline.

A safety-pin B is used for attaching the scarf-pin or similar article and is shown secured to the rear portion thereof.

Upon referring to Fig. 3 it will be noticed that the three upper flags of the series are 25 not divided from each other by a line running from the line or rope b to the outer edge of the flags, and the same may be said of the two other series of flags, which are each separated by a space, as shown.

Having described my invention, what I claim as new, and desire to secure by Letters Patent, is—

The design for a scarf-pin or similar article, as described and shown.

DONALD R. CORBIN.
